UNITED STATES PATENT OFFICE.

CHARLES S. SMITH, OF MILWAUKEE, WISCONSIN, ASSIGNOR TO A. O. SMITH CORPORATION, OF MILWAUKEE, WISCONSIN, A CORPORATION OF NEW YORK.

CORRUGATED METALLIC CAR END AND METHOD OF MANUFACTURING THE SAME.

Application filed August 31, 1921. Serial No. 497,403.

To all whom it may concern:

Be it known that I, CHARLES S. SMITH, a citizen of the United States, and a resident of the city of Milwaukee, county of Milwaukee and State of Wisconsin, have invented certain new and useful Improvements in Corrugated Metallic Car Ends and Methods of Manufacturing the Same; and I do declare the following to be a clear, exact, and complete description of the invention, such as will enable persons skilled in the art to which the invention relates to make and use the same and to practice the process of manufacture, reference being had to the accompanying drawing for an exposition of the details of a specific construction in which the concrete invention has been embodied, although it may be embodied in other forms of construction and produced by other methods of manufacture than are hereinafter disclosed.

The general nature of my invention is sufficiently outlined in the title appearing at the head of this specification.

The present activity in the development of inventions in the class to which the one now under consideration relates is directed largely to improved processes of manufacture, which are carried on with a view to reducing the costs of production attendant upon the practice of the existing methods of manufacture.

The corrugated metallic end for railway freight cars has demonstrated its serviceability and durability, and is coming into general use, both in the repair of cars now in service and in the construction of new ones.

Car ends formed of metal plates having horizontally extending corrugations, are accepted as meeting all of the requirements of the very heavy traffic burdens imposed upon cars equipped with such ends.

But the methods now followed in the manufacture of such car ends encounter obstacles which appear as structural defects in some instances, and generally involve excessive costs in production, which costs are inseparable from the production of car ends of certain types.

In constructions in which the corrugated end plate of the car and the attaching side flanges are formed from one sheet of steel, it has been necessary to reduce the plate to a state of ductility by the application of

heat, in order that the corrugations could be formed therein. But resort to this expedient greatly weakens the plate in certain areas, by reason of the unavoidable stretching of the metal which occurs when the heated plate is subjected to the drawing action of the dies of the press used in forming the corrugations. The practice also requires the maintenance of large furnaces with their consequent waste of energy, and in addition an equipment of large presses which operate with the consumption of an enormous amount of power.

My invention is designed to eliminate the defects and wastes attendant upon the practice of the older methods of corrugated metallic car end production, and I achieve the results desired by producing a corrugated car end in which there is no distension of the metal, such as follows pressing the plates as heretofore. Such a car end is produced in an exceedingly simple manner, so that I am enabled to greatly reduce the cost of production, when compared with existing methods.

In carrying out my invention, I pass a flat steel plate of appropriate gage and dimensions, through a set of fluting rollers, which impart to the plate a succession of parallel corrugations extending over the whole surface of the plate, that is, from edge to edge thereof, so that the corrugations, in the preferred structural form, will extend horizontally of the car end when the latter is later attached to the car of which it is intended to form a structural part. The side margins of the corrugated plate are folded on lines co-incident with the side lines of the car, and in such folding the corrugations in the said side margins are reduced and made to disappear in the folding pressure, so that such side margins are constituted as plane surfaces, which stand normal to the plane of the car end.

It therefore follows that the length of the corrugations in the finished end plate are co-extensive with the width of the end of the car to which the end plate is applied. The angular flanges before described as being produced in the folding operation, and which constitutes integral parts of the end plate, form the means whereby the corrugated end plate may be attached in position to the respective sides of the car.

Thus my invention greatly simplifies the

operations practiced heretofore in producing similar structures, and enables the production of corrugated metallic car ends with integrally formed attaching flanges in what 5 may be described as their simplest and most durable form.

The novel features of my invention will be pointed out in the appended claims.

In the drawing which is attached to this 10 specification,

Figure 1 is a perspective view of a part of one end of a railway freight car having a corrugated metallic car end constructed in accordance with my invention attached 15 thereto.

Fig. 2 is a plan view of a portion of a metal plate used in the production of my improved car end, and showing the plate as provided with parallel corrugations 20 extending from edge to edge thereof, the plate showing between parallel, vertical dotted folding lines, an area the width of which is equal to the width of the car end, and showing in part how the corrugated margins of 25 the plate beyond the dotted lines may be smoothed out in the folding operation to produce angular, plane flanges by means of which the corrugated end plate may be attached to the car.

Fig. 3 is a horizontal section through one corner of the car, showing the manner in which the end plate may be attached to the car structure or frame.

Referring to the drawing, the numeral 10 35 indicates a portion of the side of a railway freight car of ordinary construction, and 11 a corrugated metallic end plate constructed in accordance with my invention, and attached in position to form one end of the 40 car structure.

In the practice of my improved process, I take a flat plate 12 of sheet steel, having due regard for its necessary dimensions and the stresses to which the product will be 45 subjected while in use as a part of the car structure, and pass the said plate through a pair of fluting rollers or dies. The latter will be constructed and actuated as desired, having in mind the formation in the flat 50 plate 12 of a succession of corrugations 13 of appropriate width and height extending across the plate or from one edge to the other thereof.

A central section in the vertical direction 55 of the corrugated plate, defined by the dotted lines 14, 14, Fig. 2, and corresponding laterally with the width of the car to which the end plate is later to be applied, is preserved undisturbed, but the side margins 15, 60 15 of the plate lying outside of the said dotted lines are folded along the dotted lines so as to stand at a right angle to the plane of the plate, to form parallel flanges 17, one of which is shown, and which embrace the 65 respective sides of the car. By means of

these side flanges the corrugated end 11 may be secured in proper position as an element of the car structure.

In the folding operation referred to, the corrugations in the margins 15, 15, of the 70 plate are pressed out and made to disappear, so that such margins emerge from the press in the form of plane surfaces, 16, 16. In performing the folding operation, care should be exercised that the reserved portions of the corrugations within the area embraced by the folding lines 14, 14, are not encroached upon by the folding dies or rollers as the sheet passes therethrough.

I am aware of the fact that an end plate 80 of a structure approaching mine in similarity has been patented, but in such patented end plate the corrugations are produced by die-pressing a previously heated plate, in which operation the side margins of the 85 plate extending beyond the side lines of the car are preserved in their original planiform state to form the attaching flanges, when folded. As hereinbefore stated, an end plate produced by such older method is 90 weakened materially in certain areas by reason of the excessive stretching of the metal which occurs in the formation of the corrugations in the plate. The defects recited as inherent in the older structure are 95 eliminated in my invention.

The article embodying my invention is capable of quantity production in an expeditious and economical manner, by reason of the improved method of its manufacture. 100

The time of performing the folding operation hereinbefore described is not material, and it may be performed during the corrugation operation upon the plate or subsequently thereto.

Having thus described my invention, what I claim and desire to secure by Letters Patent of the United States, is:

1. In a car end structure, a metallic end plate having parallel corrugations extending from edge to edge thereof, such corrugated end plate having a width exceeding that of the end of the car to which it is to be attached, and parallel attaching side flanges constituted as plane surfaces out of the corrugated integral margins of the corrugated end plate which extends beyond the side lines of the car, the said attaching side flanges extending in planes normal to the vertical plane of the end plate.

2. In a car end structure, a metallic plate for use as an end plate of the car, the said plate having a width exceeding that of the car to which it is to be applied, and said plate being provided with corrugations which extend from edge to edge thereof, the corrugated integral margins of the plate extending beyond the sides of the car being folded to constitute flanges for attachment to the respective sides of the car and formed

into plane surfaces which extend normal to the plane of the end plate.

3. The process of making corrugated metallic ends for railway cars, which comprises the steps of corrugating from edge to edge a sheet metal plate having a width exceeding that of the car to which the end plate is to be applied, folding the corrugated side margins on lines coinciding with the side lines of the car, and pressing out the corrugations in such margins to form flanges having plane surfaces for attachment to the sides of the car.
4. The process of making corrugated metallic ends for railway cars, which process comprises the operations of imparting to a

sheet metal plate having a width exceeding that of the car a succession of parallel corrugations extending from edge to edge of the plate, folding the corrugated plate 20 on lines coinciding with the side lines of the car, and pressing out the corrugations in the margins beyond the folding lines to form flanges having plane surfaces for attachment to the sides of the car. 25

In testimony whereof, I have signed my name at Milwaukee, this 23d day of August, 1921.

C. S. SMITH.
